John E. Flesch, Chicago, Ill., assignor to American
Steel Foundries, Chicago, Ill., a corporation of
New Jersey

Application October 19, 1939, Serial No. 300,108

26 Claims. (Cl. 105—206)

My invention relates to four wheel railway car trucks and more particularly to a type of such truck wherein the side frame is of beam type and supports a loading member also of beam-like form. In a more or less similar well known type of truck the side frame supports a loading member in the form of a flexible semi-elliptic spring which is superposed thereon.

An object of my invention is such a car truck wherein relative movement between the sprung and unsprung members will be afforded between the two members of the truck side structure, one of which may be superposed upon the other in any one of several modifications which I have herein set forth.

A definite object of my invention is such a construction as that above described wherein the supported beam member is afforded frictional surfaces having engagement with means on the supporting side frame. My invention comprehends various arrangements wherein said supported beam may be afforded one or more diagonally arranged frictional surfaces at each end thereof suitably arranged for engagement with complementary frictional surfaces carried upon the supporting side frame.

In the drawings, Figure 1 is a half top plan view of a four wheel truck embodying my invention, Figure 2 is a half side elevation thereof, and Figure 3 is a sectional view in the vertical plane bisecting the truck transversely substantially as indicated by the line 3—3 of Figure 2.

Figure 4 is a fragmentary top plan view of a modified form of car truck embodying my invention.

Figure 5 is a half elevation, partly in section, of the structure shown in Figure 4 and Figure 6 is a sectional view therethrough in a vertical transverse plane taken substantially as indicated by the line 6—6 of Figure 5.

Figures 7 and 8 are fragmentary side elevations, partly in section, of further modifications of my novel form of car truck.

Describing the structure in greater detail and referring more particularly to the modification shown in Figures 1, 2 and 3, the truck structure comprises the bolster 2 of well known form having the center plate 4 and the side bearing 6 for abutment with a side bearing member on the supported car body. The said bolster has an end structure of bifurcated form comprising the top jaw members 8 and 10, each spanning the top member 11 of the side frame structure generally indicated at 12. The jaw end of the bolster is seated as at 13 on the member 11 and has in-

board and outboard abutment therewith as at 14, 14 and 16, 16 respectively, said seating arrangement being best understood from a consideration of Figures 1 and 3. Vertical guide lugs are afforded on the member 11 for the bolster end as indicated at 17, 17 at the outboard side and 19, 19 at the inboard side thereof. The side structure 12 is of composite form including a supporting beam or side frame 18 of general box section, best seen in the sectional view of Figure 3, with the bottom chord 20, the top chord 22, the outboard wall 24 and the inboard wall 26, said walls being cored out as at 28, 28 for convenient foundry practice. The side frame 18 is 15 of slightly arcuate form and the side walls 26 and 28 are gradually increased in depth approaching the ends thereof to a maximum at 29, 29 adjacent the integrally formed journal boxes 30, 30, said journal boxes forming the usual 20 means of connection with spaced wheel and axle assemblies (not shown). The side frame has the conventional brake hanger brackets 32, 32 integrally formed with the bottom member 18 of the side frame and conveniently located between 25 the wheels at either side of the bolster 2. At the middle of the side frame 18 the side walls 26 and 28 are extended vertically to form inboard and outboard pedestal guides 34 and 36 respectively, said pedestal guides being reinforced by 30 the vertical flanges 38, 38 and at their upper edges affording inboard and outboard abutment as at 40 and 42 (Figure 3) for the top beam member 11. The said top member 11 may be supported at either side of said guides by resilient 35 means diagrammatically indicated at 44, 44, said resilient means being seated as at 46 on the bottom wall 20 of the member 18 and projecting through openings 48, 48 formed in the top wall 22 thereof to afford seats as at 50, 50 for the member 11. The top wall of the member 18 terminates as at 52 at a point spaced from the adjacent journal box and the well 53 thus formed is defined by the shelf 54 at the base thereof, the side wall 55 of the journal box with which it 40 merges as at 56, and by the side walls 24 and 26 in the area of their greatest depth already referred to. The shelf 54 is reinforced by the vertical rib 57 extending downwardly therefrom to merge with the bottom wall 20 and the cavity under the shelf 54 is cored out as at 59 adjacent the juncture of the bottom wall 20 with the journal box. Centrally within the well 53 may be positioned a resilient member, diagrammatically indicated at 58, said resilient member 45 being afforded on its top and bottom faces with

cavities forming positioning means for engagement with lugs on the bottom of the member 11 and on the seat 54 as indicated at 60, 60. As shown, the resilient member 58 is contemplated to be in the form of a solid block of rubber-like material and accordingly space for the expansion thereof is afforded entirely therearound as best seen from the top plan view of Figure 1. Guide pads 62 and 64 are afforded on the side walls 26 and 24 within the well 53 for close engagement with the side walls at the extremity of the member 11 and the end wall of the member 11 has a close fit as at 66 (Figures 1 and 2) with the adjacent side wall of the journal box, thus confining the resilient member 58 against any except lateral expansion.

As will be seen, the beam member 11 is a very simple casting of box-like form cored out at spaced points as at 68 for convenient foundry practice.

In the embodiment shown in Figures 4, 5 and 6, the bolster 102 is identical with that of the embodiment first described with the jaw-like end 104 seated as at 106 on the top member 108 of the side frame. The member 108 may be supported on the bottom member 110 of the side frame as by resilient means diagrammatically indicated at 112 adjacent each side of the centrally formed pedestal 114, said resilient means being positioned similarly to that described for the previous modification in a well of member 110. The bottom side frame member 110 differs from that of the previous modification in the form of structure adjacent the journal box. The said member 110 is of box-like form having the bottom wall 116, the top wall 118, the inboard side wall 120 and the outboard side wall 122. The box-like structure is reinforced adjacent the end by the vertical rib 124 which reinforces the top wall 118 at the offset portion 126 adjacent the end thereof where said offset portion forms the base or bottom of the well 128, said well being defined by the adjacent wall of the journal box, the upwardly extending portions 130 and 132 (Figure 6) of the side walls of the member 110, and opposite the journal box by the wall 134 formed at the offset 136 of the top wall 118. Within the well 128 may be seated at opposite ends thereof the resilient members 138, 138 in the form of solid blocks of rubber-like material and between said resilient members 138, 138 may be positioned wedge blocks 140, 140 spaced apart as at 141, said wedge blocks having abutment against said resilient members and presenting at the upper ends thereof diagonally arranged flat friction surfaces for engagement as at 142, 142 with friction surfaces of complementary form on the end of the side frame member 108. The shape of the end portion of the member 108 is best shown in the side elevation of Figure 5 presenting flat surfaces 144, 144 converging in a downward direction for engagement with and compression between the friction blocks 140, 140. The end of the member 108 is closely confined by abutment as at 146, 146 with the side walls of the member 110, guide pads 147 accommodating this condition, and by end abutment as at 148 with lugs. In this modification space is afforded for expansion of the resilient members 138 between the walls 130 and 132 (Figure 6) and in an upward direction as seen from a consideration of Figure 5. When relative movement occurs between the top member 108 and the bottom member 110 of the side frame as by compression of the springs at 112, the V-shaped end of the member 108 will be forced downwardly between the wedge

blocks 140, 140, thus urging them apart and compressing the resilient members 138, 138 thus developing frictional absorption between said blocks and said V-shaped end.

5 In the modification shown in Figure 7 the top side frame member 202 is generally similar to those described for the previous modifications except for the end portion thereof more particularly described hereafter. The lower side frame member 204 is substantially identical with that shown in the modification of Figures 1, 2 and 3, having the well 206 adjacent the journal box 208 defined by the bottom shelf 210 reinforced by the vertical rib 212 and the widened side walls of the bottom member 204. Within the well 206 may be seated a block of resilient material 214 in abutment against the side wall of the journal box and forming a seat at its opposite side as at 216 for the wedge block 218, said wedge block having a flat surface in abutment with said resilient member and a flat bottom seat on the shelf 210 and presenting on its top surface a diagonal friction face for engagement as at 220 with the complementary face formed on the V-shaped end 222 of the member 202. The end of the member 202 is closely guided between the side walls of the member 204, guide pads 224 and 225 being formed respectively on said top member 202 and on the side walls of the member 204 for that purpose and the extremity of said member 202 has abutment as at 226 against guide lugs formed on the walls of the member 204. When relative movement occurs between the top and bottom members 202 and 204, frictional absorption will be developed at 220 and under certain conditions at 226 as will be apparent to those skilled in the art.

The modification shown in Figure 8 differs from that shown in Figure 7 principally in the form of the top member of the side frame and the manner in which the ends thereof are supported from the bottom member 304 thereof. The said bottom member is substantially identical with that described in the modification shown in Figures 4 to 6. The said bottom member 304 has the bottom wall 306, the top wall 308 downwardly offset as at 310 to the shelf 312 which merges as at 314 with the side wall of the journal box 316. The said side wall of the journal box together with the side walls of the member 304 and the transverse wall 318 define the pocket 320 within which may be seated the resilient member 322 having abutment as at 324 with the wedge block 326, said wedge block presenting opposite the side wall of the journal box a diagonally arranged friction surface for engagement as at 328 with an inwardly directed complementary friction surface formed on the end of the member 302. The end of the member 302 is thus of V-shaped form having the vertical end wall in abutment as at 330 with the side wall of the journal box so that the V-shaped end of the member 302 is confined between the side wall of the journal box and the wedge block 326. Downward movement of the upper member 302 will thus force the wedge block 326 away from the journal box, thus compressing the resilient member 322 and developing friction between the V-shaped end of the top member 302 and the opposing side wall of the journal box and the wedge 326. Under certain conditions the friction may be developed entirely between the member 302 and the wedge block 326 when there is no relative end play between the top and bottom members of the side frame. The top member 302 is closely confined between the side walls of the bottom member 304 as described for

previous modifications and in the modification now under consideration the resilient member 322 is afforded expansion upwardly and laterally.

It is to be understood that I do not wish to be limited by the exact embodiments of the device shown which are merely by way of illustration and not limitation as various and other forms of the device will, of course, be apparent to those skilled in the art without departing from the spirit of the invention or the scope of the claims.

I claim:

1. In a railway car truck, a side frame comprising a beam member of box section having integral journal boxes and pockets adjacent said journal boxes between the side walls of said member, a longitudinally extending rigid member superposed on said beam member having its ends seated in said pockets, pedestal means formed on said beam member and serving as guide means for said superposed member, resilient means interposed between said beam member and said superposed member at intermediate spaced points, resilient pads within said pockets supporting the ends of said superposed member, a load carrying member seated upon said superposed member and having thrust means engaging opposite sides thereof, and thrust means on said superposed member preventing longitudinal displacement of said load carrying member.

2. In a railway car truck, a composite side frame comprising a beam member of general box section, journal boxes integrally formed at the ends thereof, pockets between the side walls thereof adjacent said journal boxes, friction means supported in said pockets, resilient means interposed between said friction means and certain walls of said pockets, a loading member superposed on said beam member and having downwardly projecting ends received in said pockets and frictional surfaces in engagement with said friction means, other resilient means interposed between said members at spaced points between said pockets, and pedestals formed on said bottom member serving as inboard and outboard guide means for said superposed member intermediate the ends thereof.

3. In a railway car truck, a side frame in the form of a beam member of general box section, said beam member comprising journal boxes integrally formed at the ends thereof and deepened side walls forming pockets adjacent said journal boxes, friction wedge blocks resiliently seated in said pockets, a loading member having downwardly projecting V-shaped ends with friction surfaces engaged between said blocks, other resilient means supporting said loading member on said beam member at spaced points intermediate their ends, and guide means on one of said members having abutment with the other thereof intermediate said pockets.

4. In a railway car truck, a side frame comprising a beam member of box section having integral journal boxes and pockets adjacent said journal boxes between the side walls of said member, a longitudinally extending rigid member superposed on said beam member having its ends seated in said pockets, pedestal means formed on said beam member and serving as guide means for said superposed member, resilient means interposed between said beam member and said superposed member at intermediate spaced points, resilient pads positioned between the ends of said superposed member and said beam member, and a load carrying member seated upon

said superposed member and having thrust means engaging opposite sides thereof.

5. In a four wheel railway truck, a side frame comprising a beam member of box section, said beam member having integrally formed journal boxes and deepened side walls forming pockets adjacent said boxes, frictional means and a resilient pad seated in operative arrangement within said pockets, a superposed member having wedge-like end portions downwardly projecting into said pockets for engagement with and support on said frictional means, and other resilient means interposed at spaced points between said members, one of said members having pedestal means formed at an intermediate point serving as guide means for the other thereof.

6. In a side frame structure for a railway car, top and bottom beam members of box section, said bottom member having integral journal boxes, the inner walls of which merge with the bottom wall of said bottom member adjacent the bottoms of said boxes, pockets formed in said bottom member between the lateral walls thereof and adjacent said boxes, friction means within said pockets, said top member having end portions resiliently supported in said pockets for frictional engagement with said means, said resilient support comprising a pad of resilient material in abutment with said bottom member and said friction means, resilient means interposed between said members at intermediate points, and lateral guide means on said members.

7. In a four wheel truck, a side frame comprising a beam of box section with integral journal boxes at the ends thereof and pockets adjacent said journal boxes between the side walls of said beam, frictional means resiliently supported in said pockets, said resilient support comprising blocks of resilient material compressed between said frictional means and certain walls of said pockets, a member superposed on said beam and having its ends downwardly projecting into said pockets with frictional surfaces engaging said frictional means, other resilient means interposed between said beam and said member at spaced points between said pockets, and pedestal means formed on said beam intermediate the ends thereof affording inboard and outboard guide means for said member.

8. In a railway car truck, a composite side frame comprising a beam member of general box section, journal boxes integrally formed at the ends thereof, pockets between the side walls thereof adjacent said journal boxes, friction means and resilient means supported in said pockets with certain of said means abutting certain vertical walls of said pockets, a loading member superposed on said beam member and having downwardly projecting ends received in said pockets with frictional surfaces in engagement with said friction means, and other resilient means interposed between said members at spaced points between said pockets.

9. In a side structure for a railway car truck, a beam member of box section comprising integrally formed journal boxes and pockets adjacent said boxes between the side walls thereof, resilient means and wedge blocks seated in said pockets with said resilient means compressed between said wedge blocks and certain walls of said pockets, a loading member having end portions with friction surfaces in abutment with said wedge blocks within said pockets, other resilient means interposed at spaced points be-

tween said members, and pedestal guide means formed on one of said members intermediate the ends thereof for inboard and outboard engagement with the other of said members.

10. In a railway car truck, a composite side structure comprising top and bottom beam members of general box section, said bottom member comprising journal boxes integrally formed at the ends thereof and deepened side walls forming pockets adjacent said journal boxes, friction wedge blocks resiliently seated in said pockets, said top member having downwardly projecting V-shaped ends with friction surfaces engaged between said blocks, and other resilient means supporting said top member on said bottom member at spaced points intermediate their ends.

11. In a railway car truck, a side structure having top and bottom beam-like members of box section, said bottom member having upwardly opening pockets adjacent the ends thereof, a plurality of wedge blocks resiliently seated in each of said pockets, said top member having wedge-like ends downwardly projecting into said pockets in frictional engagement between said wedge blocks respectively, a plurality of resilient members interposed at spaced points between said members, and means on said members affording lateral guide means therefor.

12. In a side frame structure for a railway car, top and bottom members of box section, said bottom member having integral journal boxes, the inner walls of which merge with the bottom wall of said bottom member adjacent the bottoms of said boxes, pockets formed in said bottom member between the lateral walls thereof and adjacent said boxes, friction means within said pockets presenting friction surfaces, said top member having end portions resiliently supported in said pockets in frictional engagement with said surfaces, said resilient support including resilient means operatively arranged with said friction means within said pockets, and other resilient means interposed between said members at intermediate points.

13. In a railway car truck, a side structure having top and bottom beam members, said bottom member having at the ends thereof integral journal boxes and pockets formed adjacent said boxes, wedge blocks resiliently supported in each of said pockets, said top member having V-shaped end portions received respectively in said pockets between said blocks for frictional engagement therewith, spaced resilient means interposed between said members, and guide means on one of said members affording lateral abutment for the other thereof.

14. In a railway car truck, a side structure having top and bottom beam-like members of box section, said bottom member having upwardly opening pockets adjacent the ends thereof, a plurality of wedge blocks resiliently seated in each of said pockets, said top member having wedge-like ends downwardly projecting into said pockets in frictional engagement between said wedge blocks respectively, and a plurality of resilient means interposed at spaced points between said members.

15. In a four wheel truck, a side frame comprising a beam of box section with integral journal boxes at the ends thereof and pockets adjacent said journal boxes between the side walls of said beam, frictional means resiliently supported in said pockets, said resilient support including resilient pads compressed between said frictional means and certain walls of said pockets,

a member superposed on said beam and having its ends downwardly projecting into said pockets with frictional surfaces engaging said frictional means, and other resilient means interposed between the said beam and said member at spaced points between said pockets.

16. In a four wheel railway truck, a side frame comprising a beam member of generally box section, said beam member having integrally formed journal boxes and deepened side walls forming pockets adjacent said boxes, frictional means resiliently positioned within said pockets from certain vertical walls thereof, a loading member having end portions downwardly projecting into said pockets for engagement with and support on said frictional means, and other resilient means interposed at spaced points between said members.

17. In a side frame for a railway car, a beam member of box section comprising integrally formed journal boxes and pockets adjacent said boxes between the side walls thereof, resilient means and wedge blocks seated in said pockets, said resilient means being compressed between said blocks and certain walls forming said pockets, a loading member having end portions with friction surfaces in abutment with said wedge blocks within said pockets, and other resilient means interposed at spaced points between said members.

18. In a railway car truck, a side structure having top and bottom beam members, said bottom member having at the ends thereof integral journal boxes and pockets formed adjacent said boxes, wedge blocks resiliently supported in each of said pockets, said top member having V-shaped end portions received respectively in said pockets between said blocks for frictional engagement therewith, and spaced resilient means interposed between said members.

19. In a railway car truck, a side frame structure having top and bottom beam-like members of box section, said bottom member having upwardly opening pockets adjacent the ends thereof, a plurality of resilient pads seated in each of said pockets, wedge blocks between said resilient pads, said top member having wedge-like ends downwardly projecting into said pockets in frictional engagement between said wedge blocks respectively, and a plurality of resilient members interposed at intermediate spaced points between said members.

20. In a railway car truck, a side frame structure having top and bottom beam-like members of box section, said bottom member having upwardly opening pockets adjacent the ends thereof, resilient members abutting lateral walls of said pockets, friction blocks interposed between said resilient members, said top member having wedge-like ends downwardly projecting into said pockets in frictional engagement with said friction blocks respectively, and a plurality of resilient members interposed at intermediate spaced points between said beam-like members.

21. In a railway car truck, a side frame structure having top and bottom beam members, said bottom member having at the ends thereof integral journal boxes and pockets formed adjacent said boxes, spaced resilient members seated at opposite ends of said pockets, wedge blocks therebetween, said top member having V-shaped end portions received respectively in said pockets between said blocks for frictional engagement therewith, and spaced resilient means interposed between said beam members.

22. In a railway car truck, a side frame structure having top and bottom beam members, said bottom member having at the ends thereof integral journal boxes and pockets formed adjacent said boxes, wedge blocks and resilient pads seated in operative arrangement within said pockets, said top member having V-shaped end portions received respectively in said pockets between said blocks for frictional engagement therewith, and spaced resilient means interposed between said members.

23. In a railway car truck, a side frame structure having top and bottom beam members, said bottom member having at the ends thereof integral journal boxes and pockets formed adjacent said boxes, wedge blocks resiliently supported on each of said pockets, said top member having tapering end portions received respectively in said pockets between said blocks for frictional engagement therewith, said resilient support being disposed to resist movement of said blocks away from each other, and spaced resilient means interposed between said members.

24. In a railway car truck, a side frame comprising a bottom member of box section with integrally formed journal boxes, pockets in said bottom member adjacent to said boxes, a wedge block resiliently seated in each pocket and presenting a diagonal friction face opposite the adjacent box, a top member having a downwardly

projecting wedge-like end portion interposed between said wedge block and the adjacent journal box for frictional engagement therewith, and other resilient means interposed at spaced points between said members.

25. In a railway car truck, a side frame comprising a bottom member of box section with integrally formed journal boxes, pockets in said bottom member adjacent to said boxes, friction means in said pockets presenting diagonal wedge faces opposite said boxes, resilient means compressed between said friction means and certain walls of said pockets, a top member having wedge-like ends downwardly projecting into said pockets for frictional engagement with said friction means, and a plurality of resilient members interposed at spaced points between said top and bottom members.

26. In a railway car truck, a side frame comprising a bottom member of box section with integrally formed journal boxes, pockets in said bottom member adjacent to said boxes, wedge means in said pockets, resilient means compressed between said wedge means and said journal boxes, a top member having a wedge-like end portion received within said pockets and engaging said wedge means, and other resilient means positioned between said members at spaced points.

JOHN E. FLESCH.
